United States Patent Office.

E. K. GARDNER, OF ORVILLE, OHIO.

Letters Patent No. 70,828, dated November 12, 1867.

IMPROVEMENT IN RAILROAD GATES.

The Schedule referred to in these Letters Patent and making part of the same.

TO ALL WHOM IT MAY CONCERN:

Be it known that I, E. K. GARDNER, of Orville, Wayne county, State of Ohio, have invented certain new and useful improvements in Railroad Gates; and I do hereby declare that the following is a clear, full, and exact description of the same, reference being had to the accompanying drawings, and to the letters of reference marked thereon, in which—

Figure 1 is a perspective, and

Figure 2 a vertical transverse section, showing the mode of attaching the movable rails to the levers, by means of which the gates are operated.

To enable others skilled in the art to make and use my invention, I will now describe its construction and operation.

a a' a a' represent supports, or, more properly speaking, two railroad rails, equally divided in two parts. These parts are secured to the sills *B B*, leaving a sufficient space between them for the free working of the movable rails *C C*, as will be more clearly seen hereafter. *d d* represent cups or supports, which are secured to the under sides of the rails *a a' a a'*. The object of these supports is to retain the spiral springs *e e*, upon which the movable rails *C C* rest, and should be provided with apertures in their sides and bottoms, for the purpose of preventing an accumulation of dirt. It should be observed that the ends of the movable rails *C C* are sloped, as indicated in fig. 1. *D D* represent two gates, each of which is provided with a projection, *f*. This projection rests and slides in an aperture in support *g*. The bottom slat of the gates slides in a similar aperture in support *h*. The supports *g h* are connected by the tie *k*. *m m* are levers, the upper ends of which are confined by staples in the top slat of the gates *D D*. The lower end of these levers is provided with a slot. *n n* are also levers, bent at or about right angles, as seen in fig. 2. Said levers are connected to the movable rails by means of the arms *i i*, partly shown in fig. 2, and to levers *m m* by a bolt, through the slot above referred to. The levers *n n* are secured to the sill beneath the gates by means of the screw *x*, and the levers *m m* are bolted to the ties *k k*. It should be particularly observed that the movable rails *C C* must project a sufficient distance above the divided rails *a a'* to throw the gates back clear of the track by the action of the levers, as soon as the locomotive is upon them. Thus it will be seen the gates work automatically, for the moment the locomotive is upon the movable rails *C C*, the gates fly open or apart, and are again closed by means of the spiral springs *e e*.

The advantages of this manner of constructing a railroad gate are, first, its perfect simplicity; second, its certainty of action, as there is no way for them to become inoperative by snow or other customary obstructions, while the arrangement is such as to guarantee prompt and efficient action.

Having thus fully described my invention, what I claim, and desire to secure by Letters Patent, is—

The gates *D D*, levers *m m* and *n n*, arms *i i*, and movable rails *C C*, all combined substantially in the manner and for the purpose set forth.

In testimony that I claim the above I affix my signature in presence of two witnesses.

E. K. GARDNER.
